HARNESS FOR QUICK ATTACHABLE
CHEST PACKS

Stanley Switlik, Trenton, N. J.

Application December 7, 1934, Serial No. 756,452

22 Claims. (Cl. 244—21)

The invention relates to a quick attachable harness for parachute packs. Previously harness has been affixed or attachable to the packs, so arranged that at the time of the parachute opening, the short lift webs leading from the shoulders into the pack adjacent the body of the wearer moved upward past the face of the jumper and over the head, oftentimes injuring the face of the parachute jumper. This kind of equipment 10 was known as the floating chest type.

Experiments conducted and directed by applicant were carried on for the purpose of finding some means to prevent the pack and webs from floating. Back in the early part of 1933 applicant was successful in developing a pack and harness wherein its pack is technically of the non-floating type, and the pack held fast to the harness after having made connections between the pack and harness, the point of suspension being lowered from the shoulders to a point above the center of gravity of the body and below the shoulders. This character of harness and pack was later adopted by the United States Navy, and a small quantity was ordered and test reports since and to date have been highly satisfactory.

The fact is the purpose of this invention is to provide a new type of harness with means to afford for quick connections to a pack, wherein the point of suspension is at a point lowered from the shoulders to a point above the center of gravity and below the shoulders. This new development in harness, due to its highly satisfactory service has been found very desirable, because the one type of harness can be used interchangeably with seat, chest, and back parachute packs, the compound point of suspension being above the center of gravity and below the shoulders allows the parachute jumper to control the parachute with greater efficiency because of the lift webs being directly in front of the body and not overhead.

Furthermore the method of suspension between the connections and the lines of the parachute is the same as in all standard parachutes; that is a web is used on each connection, the closed end connected to the harness, each one of the open ends connected to one quarter of the shroud lines of the parachute maintaining this feature and also insuring the steerability of the parachute.

Let it be assumed up to the present time or at least up to the time of the recent development, that the shock load in opening has been applied to the lift webs which terminated at the shoulders

and carried the load throughout the harness from that point. However, another purpose of the invention is to provide a quick attachable harness, wherein since this recent development it has been proven that by changing the load application to a point above the center of gravity of the body and below the shoulders in front of the body, it materially reduces the shock load and applies the load far more evenly throughout the body from this point.

Still another purpose is to provide, in a quick attachable harness in combination with either a seat, chest, or back parachute pack, a construction that is self-adjustable at the time of the load application i. e., the load being applied at 15 the compound point of suspension carries the shock to the main swing, shoulder webs and pack webs, because there is a continuous webbing around the body, and therefore makes the reaction of the load all over the body and not on 20 the shoulders.

A further purpose is to provide a quick attachable harness pack, wherein the type of hook-up enables the wearer to easily handle the lift webs, as stated above, and in addition the connectible feature can be easily disconnected with as little effort as when it was first connected. This is a feature primarily necessary for water landing, and for high winds, whereby one's self 25 may easily become free from the parachute and 30 prevent being drowned or injured.

A still further purpose is to provide a quick attachable harness wherein the tie-up between the two quick attachable D rings of the pack is such, that if only one were connected the 35 parachute would function satisfactorily and save the jumper's life.

It is to be understood that the particulars herein given are in no way limitative, and that while still keeping within the scope of the invention, any desired modification of details and proportions may be made in the construction of the appliance according to circumstances.

The invention comprises further features and combination of parts to be hereinafter set forth, 45 shown in the drawings and claimed:

In the drawings:—

Figure 1 is a front view in perspective showing the improved quick attachable harness and parachute pack applied.

Figure 2 is a back view of a figure illustrating the improved harness as applied in perspective.

Figure 3 is a side view of a figure showing the improved quick attachable harness and parachute pack as applied in perspective, the pack having 55

been opened and the parachute having taken the air.

Figure 4 is a view in perspective showing the jumper in sitting posture in the swing of the harness, the parachute having taken the air and illustrating the lift webs just in front of the jumper in order that the several series of shroud cords from the parachute may be manipulated, rendering the parachute steerable.

10 Figure 5 is an enlarged detail view of certain webs of the harness in front, not only illustrating the snap hooks for rendering the pack quickly attachable to the harness and vice versa, but also showing sliding members on the webs and illustrating a snap hook and D ring connection between said slidables members.

Figure 6 is an edge view of certain of the webbing at the right hand side of the harness.

20 Figure 7 is a perspective view of the pack tray with lift webs and D rings thereon.

Figure 8 is a perspective view of the entire harness, showing the figure of the wearer in dotted lines.

Referring to the drawings it is to be noted that 25 the major portion of the harness comprises a single webbing which makes up the swing of the harness as well as providing for the front and back webs which pass over the shoulders. This single piece of webbing 1, it might be said, starts 30 at 2 passing through the adapter 3 substantially diagonally across the seat of the wearer and through an adapter 4, back through the adapter 3, through an elongated opening 5 of a snap hook 6, up the back of the wearer at 7 and over one 35 of the shoulders at 8 through an elongated opening 9 at one end of a snap hook 10, through a wrapper 11, and down under the seat and adjacent a portion of the side of the wearer, up the front on the left hand side of the wearer and then over the left hand shoulder at 12 down the 40 back, through the adapter 13 under the seat of the wearer as shown in Figure 2 and then through an adapter 14 at the left hand side as shown in Figure 2 and back through the adapter 45 13 ending at 15.

While this webbing 1 constitutes the greater portion of the seat swing and the shoulder engaging elements, there is still another webbing 16 that constitutes a substantial part of the swing 50 of the harness.

The adapter 14 through which the webbing 1 at the left in Figure 2 passes, is carried by a wrapper 17 similar to the wrapper 11. This webbing 1 where it passes through the wrapper 17 passes 55 through at 18 an elongated opening 19 of a snap hook 20. This other webbing 16 starts at 21 at the left of the wearer, passes through the elongated opening 19 of the snap hook 20 forming a loop therein and its two portions of the webbing 60 pass downwardly together and under the seat thereby forming another portion of the swing. The two portions after passing under the seat thereby forming another portion of the swing of the harness, pass upward on the right and engage the elongated opening 9 of the snap hook 10. Where engaging the elongated opening 9 the web 65 is in the form of a loop passing downwardly through the wrapper 11, the webbing 16 ending on the right of the harness. Where this webbing 16 is double just below the wrappers 11 and 17, the main web 1 engages between the double portions of the web 16. The main web 1 has a sliding connection between the double parts of the web 16 and just below where the main web 1 70 passes between the double portions of the web 16,

the web 1 is formed into loops 22, said loops engaging D rings 23 which in turn engage a snap hook 24. Other webs 21 are provided, one end of one of the webs 21 engages an elongated opening of the snap hook 24, while the corresponding 5 end of the other web 21 engages a D ring 6a. These webs 21 have their ends fastened at 28 between the double portions of the web 16 and pass between the legs substantially close to the crotch of the wearer, through adapters 29, and through 10 the D rings 23 and 6a, then back through the adapters 29 and end at 30. Slides 31 constructed of any suitable fabric, preferably canvas and folded are mounted upon those portions of the main web 1 where it passes down from the shoulders in front. The slides 31 have extensions 32, and secured between the two sides of the slides 31 are loops 33 constructed of webbing. One of the loops 33 engages an elongated opening 34 of a snap hook 35 which in turn engages with a 20 D ring 36 which is carried by the other loop 33.

The usual form of parachute pack tray 37 shown at 38 in Figures 1, 3, 4, and 7 is provided and is adapted to carry the usual parachute and shroud cords 40, as well as the lift webs 41. When 25 the pack is closed, namely the parachute folded within the tray 37 the lift webs are under the parachute, their loops 42 and extensions of the lift web being fastened at 43 to the bottom of the pack tray and connected by a cross web 44. 30 The loops of the lift webs carry D rings 45, which are designed to engage with the snap hooks 10 and 20.

It is obvious that this improved harness with the idea of having the load application above 35 the center of gravity and below the shoulders may be applied to any form or construction of parachute pack, whether it be a front pack, a back pack or a seat pack.

It is also to be understood that the tray of 40 the pack, as is shown may have a quickly breakable connection with the lift webs, so that when the parachute opens and takes the air the tray may float away. It may be that the tray of the pack may be made fast to the lift webs, so that 45 after the pack opens and the parachute takes the air, the tray may be carried by the harness throughout the decension of the jumper.

The center of gravity relative to the wearer's body as well as with relation to the point of suspension is indicated substantially on the line 50 a—a in Figure 3, approximately where the D rings connect with the snap hooks 20 as disclosed.

The invention having been set forth, what is 55 claimed is:

1. A parachute harness comprising adapters and a continuous webbing connected to and extending from one of said adapters at the small of the back of the wearer adjacent one of the sides of the wearer toward the opposite side thereof, then back again adjacent the small of the back up the back and over the shoulder at one side of the wearer's body down the front and under the rump of the wearer, and upwardly on the other side of the wearer's body up the front 60 over the shoulder of the wearer down the back and partially toward the front then back again through the other adapter adjacent the small of the back of the wearer adjacent the opposite side thereof, and then cross the wearer's back 65 and having running connection with said web constituting the last named portion which passes up the front of the wearer and then back to the last named adapter.

2. A parachute harness comprising a continu- 75

ous web, consisting of portions crossing each other adjacent the small of the wearer's back acting as a support for the wearer's back, said continuous webbing having portions extending 5 angularly up the back and crossing and passing over the shoulders and down the front toward the sides of the wearer's body and under the wearer's seat constituting a swing seat of the harness, said first mentioned crossing portions at the small 10 of the back extending into and forming a part of the second crossing portions at the top of the wearer's back and formed into loops where they constitute a part of said second crossing portions, said loops having running engagement with those 15 portions of the strap which extend down the front toward opposite sides of the wearer's body.

3. A parachute harness comprising a one piece continuous web, consisting of portions crossing each other adjacent the small of the wearer's back 20 acting as a support for the wearer's back, said single piece continuous webbing having portions extending angularly up the back and crossing and passing over the shoulders and down the front toward the sides of the wearer's body and under 25 the wearer's seat constituting a swing seat of the harness, said first mentioned crossing portions at the small of the back extending into and forming a part of the second crossing portions at the top of the wearer's back and formed into loops where 30 they constitute a part of said second crossing portions, said loops having running engagement with those portions of the strap which extend down the front toward opposite sides of the wearer's body, and a reinforcing webbing for the 35 swing seat.

4. A parachute harness comprising a one piece continuous web, consisting of portions crossing each other adjacent the small of the wearer's back acting as a support for the wearer's back, said 40 single piece continuous webbing having portions extending angularly up the back and crossing and passing over the shoulders and down the front toward the sides of the wearer's body and under the wearer's seat constituting a swing seat 45 of the harness, said first mentioned crossing portions at the small of the back extending into and forming a part of the second crossing portions at the top of the wearer's back and formed into loops where they constitute a part of said second 50 crossing portions, said loops having running engagement with those portions of the strap which extend down the front toward opposite sides of the wearer's body, and straps connected to the swing seat and to be engaged over the legs of the 55 wearer adjacent the thighs and provided with separable snap hook and D ring connections with said loops.

5. A parachute harness comprising a one piece continuous web, consisting of portions crossing each other adjacent the small of the wearer's back 60 acting as a support for the wearer's back, said single piece continuous webbing having portions extending angularly up the back and crossing and passing over the shoulders and down the front toward the sides of the wearer's body and under 65 the wearer's seat constituting a swing seat of the harness, said first mentioned crossing portions at the top of the wearer's back and formed into loops where they constitute a part of said second 70 crossing portions, said loops having running engagement with those portions of the strap which extend down the front toward opposite sides of the wearer's body, and a reinforcing webbing for 75

the swing seat and straps connected to the swing seat and to be engaged over the legs of the wearer adjacent the thighs and provided with separable snap hook and D ring connections with said loops.

6. A parachute harness comprising a one piece continuous web, consisting of portions crossing each other adjacent the small of the wearer's back acting as a support for the wearer's back, said single piece continuous webbing having portions 10 extending angularly up the back and crossing and passing over the shoulders and down the front toward the sides of the wearer's body and under the wearer's seat constituting a swing seat of the harness, said first mentioned crossing portions at the small of the back extending into and forming a part of the second crossing portions at the top of the wearer's back and formed into loops where they constitute a part of said second crossing portions, said loops having running engagement 15 with those portions of the strap which extend down the front toward opposite sides of the wearer's body, and a reinforcing webbing for the swing seat, and straps connected to the swing seat and to be engaged over the legs of the wearer adjacent the thighs and provided with separable snap hook and D ring connections with said loops, and adjustable adapters on the leg engaging straps for lengthening and shortening the same.

7. A parachute harness, comprising a one piece continuous webbing, consisting of portions crossing each other adjacent the small of the wearer's back acting as a support therefor, said single piece continuous webbing having portions extending angularly up the back and crossing and passing 30 over the shoulders and down the front toward the sides of the wearer's body and under the wearer's seat constituting a swing seat of the harness, a separable breast connection uniting those portions of the webbing which pass down the front, 35 compound suspension means carried by said portions of the webbing which pass down the front of the wearer's body adapted to connect with a parachute pack, said first mentioned crossing portions at the small of the back extending into and 40 forming a part of the second crossing portions at the top of the wearer's back and formed into loops where they constitute a part of the second crossing portions, said loops having running engagement with those portions of the strap which extend 45 down the front toward the opposite side of the wearer's body.

8. A parachute harness, comprising a one piece continuous webbing consisting of portions crossing each other adjacent the small of the wearer's back 55 acting as a support therefor, said single piece continuous webbing having portions extending angularly up the back and crossing and passing over the shoulders and down the front toward the sides of the wearer's body and under 60 the wearer's seat constituting a swing seat of the harness, a separable breast connection uniting those portions of the webbing which pass down the front, compound suspension means carried by said portions of the webbing which pass 65 down the front of the wearer's body adapted to connect with a parachute pack, said first mentioned crossing portions at the small of the back extending into and forming a part of the second crossing portions at the top of the wearer's back 70 and formed into loops where they constitute a part of the second crossing portions, said loops having running engagement with those portions of the strap which extend down the front toward 75 the opposite side of the wearer's body, said run-

ning engagement being movable in either direction to prevent excessive movement of those portions passing down the front and thereby retaining the pack against excessive movement upwardly and insuring the pack remaining substantially immediately above the center of gravity of the wearer's body.

9. A parachute harness, comprising a one piece continuous webbing, consisting of portions crossing each other adjacent the small of the wearer's back acting as a support therefor, said single piece continuous webbing having portions extending angularly up the back and crossing and passing over the shoulders and down the front toward the sides of the wearer's body and under the wearer's seat constituting a swing seat of the harness, separable breast connections uniting together those portions of the webbing which pass down the front, lift webs to be carried by a parachute pack, compound separable means on the front portions of the webbing below the breast connection and immediately above the center of gravity and to be connected to said lift webs, whereby the lift webs may position in front of the body allowing manipulation of shroud cords, said first mentioned crossing portions at the small of the back extending into and forming a part of the second crossing portions at the top of the wearer's back and formed into loops where they constitute a part of said second crossing portions, said loops having running engagement with those portions of the strap which extend down the front toward the opposite sides of the wearer's body.

10. A parachute harness, comprising a one piece continuous webbing consisting of portions crossing each other adjacent the small of the wearer's back acting as a support therefor, said single piece continuous webbing having portions extending angularly up the back and crossing and passing over the shoulders and down the front toward the sides of the wearer's body and under the wearer's seat constituting a swing seat of the harness, separable breast connections uniting together those portions of the webbing which pass down the front, lift webs to be carried by a parachute pack, compound separable means on the front portions of the webbing below the breast connection and immediately above the center of gravity and to be connected to said lift webs, whereby the lift webs may position in front of the body allowing manipulation of shroud cords, said first mentioned crossing portions at the small of the back extending into and forming a part of the second crossing portions at the top of the wearer's back and formed into loops where they constitute a part of said second crossing portions, said loops having running engagement with those portions of the strap which extend down the front toward the opposite sides of the wearer's body.

11. A parachute harness, comprising a one piece continuous webbing, consisting of portions crossing each other adjacent the small of the wearer's back acting as a support therefor, said single piece continuous webbing having portions extending angularly up the back and crossing and passing over the shoulders and down the front toward the sides of the wearer's body and

under the wearer's seat constituting a swing seat of the harness, separable breast connections uniting together those portions of the webbing which pass down the front, lift webs to be carried by a parachute pack, compound separable means on the front portions of the webbing below the breast connection and immediately above the center of gravity and to be connected to said lift webs, whereby the lift webs may position in front of the body allowing manipulation of shroud cords, said first mentioned crossing portions at the small of the back extending into and forming a part of the second crossing portions at the top of the wearer's back and formed into loops where they constitute a part of said second crossing portions, said loops having running engagement with those portions of the strap which extend down the front toward the opposite sides of the wearer's body, said running engagement constructed and arranged and constituting means whereby said portions extending down the front may be drawn taut under the buttocks or seat of the wearer to prevent excessive movement of the lift webs upwardly and retaining them in the front of the body of the wearer for manipulating shroud cords, said compound suspension means comprising D rings and snap hooks separately connecting the lift webs to the front portions of the harness, whereby upon failure of connecting certain of the D rings and snap hooks the others maintain suspension of the wearer's body.

12. A parachute harness comprising a one piece continuous web, consisting of portions crossing each other adjacent the small of the wearer's back, said single piece continuous webbing having portions extending angularly up the back and crossing and passing over the shoulders and down the front toward the sides of the wearer's body and under the wearer's seat constituting a swing seat of the harness, those portions of the webbing passing down the front having loops just immediately below the center of gravity, snap hooks for connections with lift webs of a pack adapted to be located closely adjacent the center of gravity of the wearer's body, whereby the lift webs may be operated for manipulating shroud cords, and wrappers engaged around said loops for reinforcing same, said first mentioned crossing portions at the small of the back extending into and forming a part of the second crossing portions at the top of the wearer's back and formed into loops where they constitute a part of said second crossing portions, said loops having running engagement with those portions of the strap which extend down the front toward opposite sides of the wearer's body.

13. A parachute harness comprising a one piece continuous web, consisting of portions crossing each other adjacent the small of the wearer's back acting as a support for the wearer's back, said single piece continuous webbing having portions extending angularly up the back and crossing and passing over the shoulders and down the front toward the sides of the wearer's body and under the wearer's seat constituting a swing seat of the harness, those portions of the webbing extending along the front of the wearer's body having loops, wrappers extending around said loops to reinforce same, the remote ends of those portions of the webbing crossing at the small of the wearer's back having connections with said wrappers, said first mentioned crossing portions at the small of the back extending into and forming a part of the second crossing portions at

the top of the wearer's back and formed into loops where they constitute a part of said second crossing portions, said loops having running engagement with those portions of the strap which extend down the front toward opposite sides of the wearer's body.

14. A parachute harness constructed from a web including a swing seat provided with side portions, a reinforcing web conforming to the swing seat, said reinforcing web having terminal loops at its side portions, a compound suspension means carried by said loops located adjacent to center of gravity of the wearer's body and adapted for connection with a parachute pack.

15. 15. A parachute harness constructed from a web including a swing seat provided with side portions, a reinforcing web conforming to said swing seat, said reinforcing web having terminal loops at its side portions, compound inverted suspension means carried by said loops located adjacent to center of gravity of the wearer's body and adapted for connection with a parachute pack when the latter is moved upwardly to make the connections.

25. 16. A parachute harness constructed from a web including a swing seat provided with side portions, a reinforcing web conforming to said swing seat, said reinforcing web having terminal loops at its side portions, compound suspension means comprising snap hooks carried by said loops located adjacent to center of gravity of the wearer's body and adapted for connection with a parachute pack.

35. 17. A parachute harness constructed from a web including a swing seat provided with side portions, a reinforcing web conforming to said swing seat, said reinforcing web having terminal loops at its side portions, compound suspension means comprising snap hooks carried by said loops located adjacent to center of gravity of the wearer's body and adapted for connection with a parachute pack, said hooks inverted, whereby devices on a parachute pack may be engaged therewith when moving the pack upwardly.

45. 18. A parachute harness constructed from a web including a swing seat provided with side portions, a reinforcing web conforming to said swing seat, said reinforcing web having terminal loops at its side portions, compound suspension means comprising snap hooks carried by said loops located adjacent to center of gravity of the wearer's body and adapted for connection with a parachute pack, said hooks having openings

through which said first named web passes reinforcing said suspension means.

19. A parachute harness constructed from a web including a swing seat provided with side portions, a reinforcing web conforming to said swing seat, said reinforcing web having terminal loops at its side portions, compound suspension means comprising snap hooks carried by said loops located adjacent to center of gravity of the wearer's body and adapted for connection with a parachute pack, said hooks having openings through which said first named web passes reinforcing said suspension means, and wrappers fastened around said loops thereby additionally reinforcing said suspension means. 15

20. A parachute harness, comprising a continuous web, consisting of portions passing up the back and over the shoulders and under the wearer's seat and formed into a swing seat, the side portions of the swing seat having terminal loops 20 closely adjacent to center of gravity of the wearer's body, and compound suspension means carried by said loops and adapted for separable connections with a parachute pack.

25. 21. A parachute harness, comprising a continuous web, consisting of portions passing up the back and over the shoulders and under the wearer's seat and formed into a swing seat, the side portions of the swing seat having terminal loops 30 closely adjacent to center of gravity of the wearer's body, and compound suspension means carried by said loops and adapted for separable connections with a parachute pack, and additional webs at the small of the wearer's back certain of the additional webs having operative 35 adapter connections with said loops and including wrappers reinforcing said loops.

22. A parachute harness, comprising a continuous web, consisting of portions passing up the back and over the shoulders and under the wearer's 40 seat and formed into a swing seat, the side portions of the swing seat having terminal loops closely adjacent to center of gravity of the wearer's body, and compound suspension means carried by said loops and adapted for separable connections with a parachute pack, and additional webs at the small of the wearer's back certain 45 ends of the additional webs having operative adapter connections with said loops and including wrappers reinforcing said loops, other portions 50 of said additional webs having running engagements with the sides of the swing seat.

STANLEY SWITLIK.
